[57] **CLAIM**

The ornamental design for a deer call, as shown and described.

DESCRIPTION

FIG. 1 is a pictorial representation of a deer call showing my new design, the deer call being connected about a person's leg which is shown in phantom for illustrative purposes only.

FIG. 2 is a perspective view of the deer call;

FIG. 3 is a top plan view thereof;

FIG. 4 is a bottom view thereof;

FIG. 5 is a side elevational view of one side thereof;

FIG. 6 is a side elevational view of an opposite side thereof;

FIG. 7 is a front elevational view thereof; and,

FIG. 8 is a rear elevational view.
